Primary Examiner—James Gandy*Assistant Examiner*—Robert M. Spear*Attorney, Agent, or Firm*—David M. Weirich; Steven W. Miller; Jacobus C. Rasser**[57] CLAIM**

The ornamental design for a pair of seams for disposable article, as shown and described.

DESCRIPTION

The sole FIGURE is a top plan view of a pair of seams for disposable article, showing our new design.

The broken lines showing a disposable article are for illustrative purposes only and form no part of the claimed design.
